UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CARBURETER.

1,225,398.

Specification of Letters Patent.

Patented May 8, 1917.

Application filed August 5, 1914. Serial No. 855,196.

To all whom it may concern:

Be it known that I, REUBEN B. BENJAMIN, a citizen of the United States, residing at Chicago, in the county of Cook and State 5 of Illinois, have invented new and useful Improvements in Carbureters, of which the following is a full, clear, concise, and exact description, reference being had to the accompanying drawing, forming a part of 10 this specification.

My invention relates to carbureters for internal combustion engines.

It is one of the objects of my invention to provide a carbureter in which delivery of 15 the fuel to the mixing chamber in globules is avoided.

Further objects of my invention are to provide a carbureter in which undue wear in the moving parts is eliminated; to provide a carbureter that is readily adjustable; 20 and to provide a carbureter that is economical to manufacture and efficient in its operation.

Additional objects and advantages of my 25 invention will be apparent from the following description taken in connection with the appended claims.

In the following specifications and accompanying drawings I have described and 30 illustrated a carbureter constructed in accordance with my invention, but it is to be clearly understood that numerous changes may be made in the form, construction and arrangement of the parts without departing 35 from the spirit of my invention or exceeding the scope of the appended claims, the forms of the invention herein disclosed being merely preferred embodiments thereof.

40 In the drawings:

Figure 1 is a vertical cross-sectional view of a carbureter constructed in accordance with my invention.

Fig. 2 is a vertical cross-sectional view 45 of a modified form of my device.

Fig. 3 is a top view of the rotor.

Fig. 4 is a section on the line 4-4, Fig. 1; and

Fig. 5 is a section on the line 5-5, Fig. 2. 50 Referring now to the modification of Fig. 1:

The carbureter has a fuel chamber 6, in which is a floating member 7, carried by an arm 8 pivoted to the casing as at 9 and embracing a needle valve 10, which regulates 55

the admission of the fuel from the tank to retain the same at a substantially constant level. In the center of the fuel chamber the casing forms an air passage 11, which communicates with a main air intake port 12. 60 This air passage is slightly contracted at the top to provide a valve seat portion 12^a. The fuel valve 13, rotor 14, and sleeve 15 are suitably mounted on a stem 16.

The valve 13 and stem 16 are secured to 65 member 14 to rotate therewith, the valve having a fuel-spreading portion 13^a, tapering outwardly and away from the fuel outlet port 13^b.

The sleeve 15, in which the stem 16 rotates, is engaged by a lever 17 having a fulcrum on the casing as at 18 and pivoted to a rod 19.

The opening of the valve 13 is opposed by a coil spring 20, encircling the rod 19, which 75 spring can be adjusted by means of the nut 21 to give the proper resistance.

The rod 19 is connected in a suitable manner with the accelerator, and it will be apparent that its depression will cause an 80 increased displacement of the valve.

To prevent injury to the lever 17 by an undue pressure on the rod 19, the displacement of the latter is limited by a stop 22, comprising a screw 22^a which can be removed to allow the fuel chamber to be drained when desired. The fuel flows from the supply chamber through the passage 23 to the outlet port 13^b. A lubricating passage 24 leads to the lower end of the stem 16. 90

The pipe 25 leading to the intake manifold is provided with a butterfly valve 26. The valve 13 is rotated by means of the rotor 14, which comprises a disk mounted at the top of the valve and having blades 27 95 struck up therefrom. The air passing up through the passage 11 strikes these blades, causing the rotation of the member 14 and the valve 13 secured thereto.

The rotor 14 has a down-turned flange 100 14^a, which rotates in an annular channel 28, the purpose of this construction being to prevent the air from flowing around the edges of the rotor and to direct it through the openings 14^b therein against the 105 blades 27.

The valve 13 has secured thereto by means of arms 29 a tubular air-directing member 30 for causing the air to flow in a thin sheet over the surface of the film of fuel on the 110

fuel-spreading portion 13^a to insure a thorough mixing of the air and fuel. The upper edge of the member 30 acts as an auxiliary air valve coöperating with a valve 5 seat portion 12^a.

In operation the vacuum produced by the engine causes the valve 13 to lift against the resistance of the spring 20, opening the port 13^b to allow the passage of the fuel. At 10 the same time the vacuum produced by the engine causes air to be drawn through the annular passage between the valve 13 and the air directing member 30 and through the openings 14^b in the rotor 14 causing the 15 latter and with it the valve 13 to rotate. The rotation of the valve and the shape of the portion 13^a cause the fuel to be spread in a thin film over the surface of the valve. As the air is directed in a thin sheet over 20 the surface of the film of fuel the air and fuel are thoroughly mixed.

As the member 30 is lifted because of the vacuum due to the operation of the engine an auxiliary air passage is opened between 25 the upper edge 31 of the member 30 and the valve seat portion 12^a, said opening varying with the amount of lift, the air opening thus being proportional to the fuel opening and the opening of both proportional to the degree of vacuum produced by 30 the engine.

In the modification of Fig. 2 a conical air-directing member 32 is secured to the valve 13 by means of arms 33. The lower edge 32^a 35 of the member 32 acts as an auxiliary air valve coöperating with the valve seat portion 34. In operation the vacuum produced by the engine causes the valve 13 to be lifted and rotated, causing the fuel to be spread in 40 a thin film over the surface of the valve. At the same time air is drawn through the annular passage between the valve 13 and the air-directing member 32, the air being thus directed in a thin sheet over the film 45 of fuel, causing a thorough mixture. As the member 32 is lifted, an auxiliary air passage is opened between the lower edge 32^a of the member 32 and the valve-seat portion 34, said opening varying with the amount of 50 lift.

It is to be noted that in both modifications, the fuel, the air admitted through the primary air passage between the air-directing member 32 and the valve 13, and the air 55 directed through the auxiliary air passage, must all pass between the edge of the larger end of the valve 13 and the valve seat or throttle portion 12^a. Because of the comparatively large circumference of the valve 60 13, the distance between the upper edge of this valve and the inner edge of the valve seat or throat portion 12^a may be comparatively small, causing the fuel and the air admitted through both the primary and the 65 auxiliary air passages to flow through a

narrow annular passage between the upper edge of the valve 13 and the throat portion 12^a, insuring a thorough mixture of the fuel and the air admitted through the primary air passage with the air admitted through 70 the auxiliary air passage.

Having thus described my invention, what I claim as new and desire to secure by Letters Patent is:—

1. In a carbureter, the combination with a 75 fuel supply and an air supply, of means for controlling the flow of fuel from said supply, comprising a conical rotating member, means for causing the fuel to flow in a thin film over the surface of said member 80 toward its larger end, and means movable with said rotating member for causing the air to flow in a thin sheet over said film.

2. In a carbureter, the combination with a 85 fuel supply and an air supply, of means for controlling the flow of fuel from said supply, comprising a rotatable tapering member, means for causing the fuel to flow in a thin film over the surface of said member 90 toward its larger end, and tubular means carried by said rotatable tapering member and substantially coaxial therewith, for causing the air to flow in a thin sheet over 95 said film.

3. In a carbureter, the combination with a 95 fuel supply and an air supply, of means for controlling the flow of fuel from said supply, comprising a tapering member, means for causing the fuel to flow in a thin film over the surface of said member toward 100 its larger end, and movable means surrounding said tapering member and adjacent thereto for causing the air to flow in a thin sheet over said film and for controlling the admission of an additional supply of air to 105 the fuel.

4. In a carbureter, the combination with a fuel supply and an air supply of means for controlling the flow of fuel from said supply, comprising a tapering member, 110 means for causing the fuel to flow in a thin film over the surface of said member toward its larger end, and tubular means carried by said tapering member and substantially coaxial therewith, for causing the air to 115 flow in a thin sheet over said film and for admitting an additional supply of air to said fuel.

5. In a carbureter, the combination with a fuel supply and an air supply, of a fuel 120 outlet port, a member comprising a needle valve portion controlling said port, and a portion tapering outwardly away from said port and a movable tubular member surrounding said first member and adjacent 125 thereto, for causing the air to flow in a thin sheet over the surface of said tapering part, said tubular member also comprising valve means for controlling the admission of an additional supply of air.

6. In a carbureter, the combination with a fuel supply and an air supply, of a fuel outlet port, a member comprising a needle valve portion controlling said port, and a portion tapering outwardly away from said port and a tubular member surrounding said first member and adjacent thereto, for causing the air to flow in a thin sheet over the surface of said tapering part, said tubular member also comprising valve means for controlling the admission of an additional supply of air, said tubular member being carried by said first member.
7. In a carbureter, the combination with a fuel supply and an air supply, of a fuel outlet port, a member comprising a needle valve portion controlling said port, and a portion tapering outwardly away from said port, and a tubular member surrounding said first member and adjacent thereto, for causing the air to flow in a thin sheet over the surface of said tapering part, said tubular member also comprising valve means for controlling the admission of an additional supply of air, said tubular member being carried by said first member, said valve member opening in the direction of flow of the air, and spring means resisting the opening of said valve.
8. In a carbureter, the combination with a fuel supply and an air supply, of a fuel outlet port, a member comprising a needle valve portion controlling said port and a portion tapering outwardly away from said port, a tubular member surrounding said first member and adjacent thereto, for causing the air to flow in a thin sheet over the surface of said tapering part, and means for rotating said first member.
9. In a carbureter, the combination with a fuel supply and an air supply, of means for controlling the flow of fuel from said fuel supply, comprising a fuel valve having an enlarged portion, said air supply having a throat portion adjacent to said enlarged valve portion, whereby the fuel is caused to flow between the inner edge of said throat and the enlarged portion, means whereby on opening said valve a primary current of air will flow through said throat around said enlarged portion, and means whereby, on further opening of said valve, an auxiliary air current will flow through said throat around said enlarged portion.
10. In a carbureter, the combination with a fuel supply and an air supply, of means for controlling the flow of fuel from said fuel supply, comprising a fuel valve having

an enlarged portion, said air supply having a throat portion adjacent to said enlarged valve portion, whereby the fuel is caused to flow between the inner edge of said throat and the enlarged portion, means whereby on opening said valve a primary current of air will flow through said throat around said enlarged portion, means whereby, on further opening of said valve, an auxiliary air current will flow through said enlarged portion, and means for rotating said valve.

11. In a carbureter, the combination with a fuel supply and an air supply, of means for controlling the flow of fuel from said supply, comprising a fuel port and a needle valve having an inverted conical portion extending above said port, the upper part of said conical portion being of comparatively large circumference, said air-supply means comprising a throat portion surrounding the upper part of said valve, the distance between the upper part of said valve and the inner edge of said throat being comparatively small, whereby a narrow annular passage is formed therebetween, means whereby, on opening the fuel valve, a primary current of air will flow through the narrow annular passage, and means whereby, on further opening of the valve, an auxiliary air current will flow through said narrow annular passage.

12. In a carbureter, the combination with a fuel supply and an air supply, of means for controlling the flow of fuel from said supply, comprising a fuel port and a needle valve having an inverted conical portion extending above said port, the upper part of said conical portion being of comparatively large circumference, said air-supply means comprising a throat portion surrounding the upper part of said valve, the distance between the upper part of said valve and the inner edge of said throat being comparatively small, whereby a narrow annular passage is formed therebetween, means whereby, on opening the fuel valve, a primary current of air will flow through the narrow annular passage, means whereby, on further opening of the valve, an auxiliary air current will flow through said narrow annular passage, and means for rotating said valve.

In witness whereof, I have hereunto subscribed my name in the presence of two witnesses.
